PAPER GARMENT AND METHOD OF
MAKING SAMESylvia Trokie and Hazel McKechnie,
New York, N. Y.

Application November 2, 1946, Serial No. 707,462

2 Claims. (Cl. 2—243)

1

Our present invention relates generally to paper garments and a novel method of fabricating same, and more specifically to an improved crepe paper costume and method of making the bodice or waist section thereof.

Crepe paper costumes, particularly those used by children for masquerades or parties, need to have a design and construction such that they simulate the original garment. After considerable experimentation we have found that in order to manufacture a paper garment, such as a crepe paper costume, so that it is both effective and durable the waist or bodice section thereof should be lined with a textile material. For example, a lining material, such as buckram, has been found by us to be highly advantageous. The buckram lining concurrently was found to act as a guard for the wearer's body against the dye in the crepe paper. An additional advantage in lining the paper bodice proved to be the fact that the bodice functioned as a firm foundation for securing the skirt waist hem and desired sleeve trimmings. The lined bodice, also, makes it possible to construct the dorsal or back sections in two panels thereby making it possible to put the costume on without slipping it on over the head.

The manufacture of the paper garment of our present invention presented a problem. Crepe paper, for example, has considerable stretch due to its crinkly structure. Upon cutting both the crepe paper and the lining material to the same pattern, we found in sewing them together that the crepe paper stretched and slipped so that the finished bodice was very often distorted or torn. The method was, also, time consuming. We solved this problem in a simple manner by first cutting the lining material to the desired pattern, then stitching the patterned lining to an unformed crepe paper without stretching or slippage of the paper, and finally cutting the crepe paper to match the lining pattern. We found that this method of fabricating the waist or bodice section effectively and completely solved our problem.

Still other features of our invention will be apparent from the following detailed description taken in connection with the drawing, in which:

Fig. 1 is a front view of a crepe paper costume embodying our invention;

Fig. 2 shows the rear view of the costume;

Fig. 3 shows the interior of the bodice section of the garment spread out;

Fig. 4 illustrates a patterned buckram lining for the front panel or section of the bodice; and

Fig. 5 illustrates our method of stitching the patterned lining of Fig. 4 to the sheet of unformed crepe paper.

2

Referring now to the accompanying drawing, wherein like reference numerals denote similar elements, we have chosen to explain our invention with a dress costume used by girls in dancing classes or ballet. It is to be clearly understood, however, that we do not limit ourselves to dresses. For example, the invention is applicable to graduation gowns made of crepe paper, or to costumes worn by boys.

Considering the dress shown in Figs. 1, 2 and 3, it consists of a bodice or waist section 1, a skirt 2 and sleeve trimmings 3. These are all made of crepe paper, and dash lines 4 and 5 denote the respective stitch lines for the skirt and sleeve trimming. Of course, the skirt and sleeve trimming or ruffles may be of any design desired. The sleeve ruffles 3 can be full or short length, if desired. As shown in Fig. 2 the dress is open at the back, as indicated by line 1. The bodice 1 is composed of a front section 8 and two back sections 9 and 10. The upper and lower ends of the back sections 9 and 10 are provided with two pair of tie tapes. Thus, numerals 11, 11' designate the upper pair of tie tapes or cords sewed to alternate sides of line 7. Numerals 12, 12' denote the lower pair of tie tapes sewed to the juncture of skirt and bodice on alternate inner and outer faces, as indicated in Fig. 3. By making the back sections of the bodice in two parts 30 it is readily possible to eliminate the need for slipping the costume over the head.

As shown in Fig. 3 the bodice sections 8, 9 and 10 are provided with fabric linings 8', 9' and 10' respectively. Dash line 20 denotes the stitching 35 for securing the lower edges of the bodice crepe paper sections to the lower edges of the respective lining. The stitch line 4, as stated before, secures the skirt to the bodice. The dash line 21 denotes the stitching for securing the upper edges 40 of the bodice sections to the lining edges. Stitch lines 30 and 31 of the bodice provide the folded hems 30' and 31' of the back sections of the bodice. The shoulder stitchings 40 and 41 secure the upper strap edges of the front section 8 and the back sections 9 and 10. The dash lines 50 and 51 designate the respective stitch lines between the armpits and the waist of the respective front and back sections. The arm stitching 60 and 61 between the crepe paper and lining of each of the front section and back sections completes the stitch lines for the bodice. If desired, darts 80 and 81 may be provided by suitable stitching of the front section 8 and the pair of back sections 9 and 10. The lining 8', 9' and 10', which we prefer to make of buckram, provides a firm character to the

bodice. As a result of the bodice lining construction the costume is both effective and durable. It has been found in actual practice that the garment can be worn over and over again without any substantial damage to the bodice section. Furthermore, the lining effectively guards the body of the wearer from the dye in the crepe paper. The bodice provides a firm foundation to which may be sewed the skirt and sleeve sections. This cannot be done where the bodice is made of crepe paper and no lining is used. Finally, the entire costume presents a tailored appearance by virtue of the fact that the bodice crepe paper adheres smoothly and without wrinkles to the buckram lining.

We attribute these characteristics of the bodice to our novel method of manufacturing the latter. In Fig. 4 and Fig. 5 we show an illustrative sequence of steps for manufacturing the front section of the bodice, although our method is not limited to the illustrative steps. Assuming that numeral 90 in Fig. 4 illustrates the buckram lining of a front section, such as 8' in Fig. 3, it will be understood that we first cut the buckram lining 90 to the desired pattern as indicated in Fig. 4. In accordance with our method we do not stitch the pattern lining to a corresponding patterned crepe paper. On the contrary we stitch the patterned lining 90 to a piece of crepe paper 91, shown in Fig. 5, the crepe paper being formless. The dash lines 92 indicate the stitch for securing the border of lining 90 to the formless crepe paper 91.

The next step is to cut the crepe paper in Fig. 5 so as to match the shape of the lining. We have found by actual experience that if both the crepe paper and lining material were cut to the desired pattern, then the crepe paper stretched and slipped with the result that the finished bodice was very often crooked and torn. Further, this method was very slow due to the difficulty of handling the crepe paper. However, by using our present method no stretching or slippage is encountered, because the unformed sheet has an

opportunity to conform and accommodate itself to the lining pattern during sewing. When the crepe paper 91 is cut the resultant bodice section has a firm foundation, and it is found that the crepe paper is smooth and undamaged. Moreover, this method is relatively fast. Of course, the back sections of the bodice would be produced in the same manner as described in connection with Figs. 4 and 5.

10 What we claim is:

1. A method of forming a garment from paper constructed to have considerable stretch which includes the following steps: cutting a relatively stiff fabric lining to a predetermined pattern, then 15 stitching the fabric lining to an entire uncut sheet of said paper along the edge of the lining to cause the sheet to conform and accommodate itself to said lining pattern during stitching, and finally cutting the paper along the outline of the patterned lining to provide a lined paper pattern wherein the paper adheres smoothly and without wrinkles to the lining.

25 2. A method of manufacturing the bodice of a crepe paper costume, which includes the steps of stitching a patterned buckram lining along the edges thereof to an unformed sheet of crepe paper which is substantially larger than the area of the lining to cause the crepe paper sheet to conform and accommodate itself to the lining pattern during stitching, and then cutting the 30 patterned lining to the outline of the lining.
